COMBINED PEN AND LETTER OPENER

Irwin Ross, 50—36 Horatio Parkway, Bayside, N.Y.

Filed Mar. 8, 1961, Ser. No. 64,187

Term of patent 14 years

(Cl. D74—17)

FIG. 1 is a front elevational view of a combined, pen and letter opener, showing my new design;

FIG. 2 is an edge elevational view thereof;

FIG. 3 is an end view looking at the left side of FIG. 2;

FIG. 4 is an end view looking at the right side of FIG. 2;

FIG. 5 is a sectional view taken along line 5—5 of FIG. 2 in the direction of the arrows; and

FIG. 6 is a sectional view taken along line 6—6 of FIG. 2 in the direction of the arrows.

I claim:

The ornamental design for a combined pen and letter opener, as shown.
